ADJUSTABLE STILT

Benjamin F. Taylor, Pontiac, Mich.

Application July 8, 1936, Serial No. 89,554

4 Claims. (Cl. 272—70.1)

My invention relates to stilts of adjustable character.

The main objects of this invention are to provide an improved form of stilt which is readily adjustable by the user; to provide a stilt which may be adjusted as to length and height of the foot rest above the ground by the user while the stilt is in use; to provide a stilt of simple construction and of economic manufacture; to provide a stilt in which the weight of the person on the stilt will be very close to the point of support of the end of the stilt upon the ground and thereby have very little tendency to pull the stilt away from the body of the user; to provide a stilt which may be readily locked in adjusted position in a simple manner; and to provide a stilt in which the locking of the stilt in adjusted position is maintained by the weight of the user upon the stilt step, and to provide a stilt of simple and durable construction.

An illustrative embodiment of the invention is shown in the accompanying drawing, in which:

Figure 1 is a view in elevation of the improved stilt with a portion of the wall of the tube broken away to show the openings in the wall that receive the adjusting and locking lug with the shoe shown in section.

Figure 2 is a plan view of the improved stilt.

Figure 3 is a view in side elevation of the foot or shoe at the bottom of the stilt with a fragmentary portion of the stilt.

Figure 4 is a sectional view taken on the line 1—1 of Figure 1.

In the construction shown in the drawing the stilt comprises a pair of telescoping tubes 1 and 2 of circular cross-section with the exception of flattened sides 3 and 4 respectively which interengage when the two tubes are in telescoping relation so as to prevent relative rotation between the tubes while at the same time permitting free axial movement therebetween for adjusting purposes.

The lower end of outer tube 2 is surrounded by a clamping ring 5 rigidly secured thereto and preferably in the form of a metal strap curved so as to fit the contour of the tube 2 with the terminating ends thereof bent radially and in spaced relation to each other forming a pair of spaced parallel lugs 11 and 11A. The lugs 11 and 11A are provided with openings therethrough in registry and are adapted to receive a lug 10 therebetween, which is similarly provided with an aperture through which extends a combined clamping and pivot bolt 9.

55 The lug 10 is an integral part of the step 6

which extends laterally from the stilt a sufficient distance to receive the foot of the user, the top surface 8 thereof may be roughened or corrugated to prevent slippage of the foot placed thereon. The step 6 extends downwardly and inwardly from the main body portion thereof in the form of an arm 7 and is provided near its lower termination with a laterally extending boss 12 formed on the side of the arm 7 adjacent to the stilt.

The inner tube 1 is provided with a plurality of 10 axially spaced aligned slots or openings 14 which are adapted to snugly receive the boss 12, which boss serves as a lock to maintain the tubes in adjusted telescoped relation with respect to each other. The lower end of the arm 7 may be provided with a semi-circular shoe or band 13 which 15 partially surrounds and slidably engages the adjacent face of the tube 1 for the purpose of providing a substantial bearing for the lower end of the arm and foot support, and for guiding the boss 12 into engagement with the slots 14 when it is desired to adjust the tubes with respect to each other for varying the overall length of the stilt.

The lower end of tube 1 which normally 20 will come in contact with the ground is provided with a shoe 15 which provides ample and sufficient bearing surface so that the lower end of the relatively small stilt will not embed itself in soft ground or the like and interfere with the normal use of the device and for the purpose of 25 preventing slippage on pavement or the like. The shoe may be provided with either a corrugated bottom surface or may be rubber covered as desired.

In the use and operation of the stilt, the foot 35 support 6 is swung upwardly as shown in dotted outlines in Figure 1 of the drawing, and the tubes 1 and 2 slide axially with respect to each other to the approximate position as nearly as can be estimated by the user, then the foot rest is swung 40 back to its normal position with the lug 12 engaging in the adjacent slot 14, slight adjustment being necessary to secure this engagement as a 45 relatively tight or snug fit is desirable, so that it will not be accidentally displaced in use. The person using the stilt then mounts upon the steps in the usual manner, holding the outer tube 2 50 grasped in the hand with the stilt resting alongside of the body and back of the shoulder in the usual manner.

Should it be desired to adjust the stilt further, this may be done even while mounted upon the stilt by simply slipping the foot under and raising the foot rest 6 momentarily and then lifting up on the outer or upper tube 2, the weight of the lower 55

tube will cause it to slide downwardly axially, and when the desired height is reached, the foot is again slipped out on top of the foot rest 6 and immediately upon the lug 12 sliding down and reaching the next slot below the position at which it is during the adjusting movement, it will be forced automatically into the slot 14 and thus the two tubes will be relocked in adjusted position.

It will be noted that by the use of two relatively small telescoping tubes the weight of the person mounted upon the foot step 6 is offset but very slightly with respect to the point at which the bottom end of the stilt rests upon the ground; that is to say that there will be very little leverage exerted upon the upper part of the stilt 2, and it can be maintained in proper position at the shoulder very readily and particularly as compared to stilts of general character in which the step upon which the foot rest is offset considerable with respect to the point at which the foot rests on the ground.

By having a foot of suitable size which may be varied under different circumstances on the lower end of the stilt, it is possible to utilize relatively small and light weight tubing and still have a good bearing for the lower end of the stilt to meet the bearing conditions when in use.

Although but one specific embodiment of this invention has been herein shown and described, it will be understood that numerous details of the construction shown may be altered or omitted without departing from the spirit of this invention as defined by the following claims.

I claim:

1. A stilt comprising a pair of hollow standards having flat mated sides, which standards are adjustable lengthwise with respect to each other, a foot rest or support hinged on one of such standards to swing upwardly from normal position, said other standard having a series of open-

ings and a lug on said foot support adapted to engage the openings in the other of said standards for locking the standards against relative movement.

2. A stilt comprising a pair of hollow telescopic members having flat mated sides with one member movable within the other for adjustment lengthwise with respect to each other, a foot support movably mounted on the outer of said members, said inner member having a series of openings and means on said foot support for engaging said openings in the inner of said members for positively locking said members against relative movement.

3. A stilt comprising a pair of telescoping members one movable within the other for adjustment lengthwise with respect to each other, a foot support hingedly mounted on the outer of said members, said inner member having a series of openings, a lug on said foot support for engaging said openings in the inner of said members for locking said members against relative movement, and positioning means on said foot support for guiding said lug relative to said opening.

4. A stilt comprising a pair of telescoping members adjustable lengthwise with respect to each other, a clamping band surrounding the outer of said members closely adjacent to one end thereof, a foot rest hinged to said clamping band, said foot rest having a supporting arm thereunder, the inner of said members being provided with a plurality of axially spaced aligned openings, a lug on said foot support arm adapted to enter and engage a selected opening in said inner member, and guides at each side of said locking lug for facilitating the entry of said lug into such selected opening.
